M. RYLL.
MOVABLE TOY FIGURE,
APPLICATION FILED MAY 20, 1919.

Patented Mar. 23, 1920.

FIG. 1.

FIG. 2.

FIG. 3.

FIG. 4.

Inventor
Martin Ryll

By *Adam S. Schatz* Attorney

UNITED STATES PATENT OFFICE.

MARTIN RYLL, OF PORT COLBORNE, ONTARIO, CANADA.

MOVABLE TOY FIGURE.

1,334,939.

Specification of Letters Patent. Patented Mar. 23, 1920.

Application filed May 20, 1919. Serial No. 298,494.

To all whom it may concern:

Be it known that I, MARTIN RYLL, a citizen of Poland, residing at Port Colborne, Province of Ontario, and Dominion of Canada, have invented certain new and useful Improvements in Movable Toy Figures, of which the following is a specification.

This invention relates to improvements in toys and has for its principal object to provide a toy comprising a figure of which the legs and arms are movable and means for operating the same.

Another object of the invention resides in the provision of a toy made to simulate a violinist in the act of playing a violin.

With these and other objects in view as will become apparent as the description proceeds, the invention consists in the novel construction, combination and arrangement of parts, as will be fully set forth in the following specification, claimed and illustrated in the accompanying drawings in which—

Figure 1 is a face view of the device.

Fig. 2 is a view similar to Fig. 1 showing the same in another position.

Fig. 3 is an enlarged view partly in section taken on line 4—4 of Fig. 1, and

Fig. 4 is a detail showing the connection between the bow and hand.

Referring to the drawings in detail, the numeral 1 designates the body portion of the figure which is provided at its upper end with the head portion 2. Pivoted to the lower end of the body portion, as at 3, are the articulated leg portions 4 carrying at their lower ends the feet portion 5.

Pivoted to the body portion 1 near its upper end at 6 is the arm member 7 to which the bow is attached, while an arm 8 is pivoted, as at 9, to the opposite side of said body portion in a plane with the arm 7. The body 10 of the violin is fixed on the arm 8 and is provided with, the usual neck 11, which is attached to the hand 12 formed on the end of the arm 8 by the pivot 13.

Connecting the hand 14 formed with the arm 7, to the bow 19 is a pivot 24 provided with a radial lug 25 which operates in a slot 26 in the bow 19 in order to limit its movement as will be clearly seen upon reference to Fig. 4.

The violin bow comprises a body 15 which is slotted as at 16 to receive the hand 14 carried at the end of arm 7. The body 15 is provided with a pair of parallel longitudinal extensions 18 and 19 which form a slot 17 through which the violin body 10 is slideable. A connecting member 20 joins the outer ends of the extensions 18 and 19.

In order to operate the figure, a pull cord 21 is provided and has attached thereto the outwardly extending cords 22, and 23 the ends of which are secured as at 24 and 25 near the upper ends of the legs and arms respectively. It will thus be seen that when the cord is pulled the limbs will be elevated and as soon as the cord is relaxed the limbs will return to their lowered position. It will also be noted that the movement of the arms is in opposite directions and therefore operation of the device will cause the bow to move over the violin body.

While in the foregoing there has been shown and described the preferred embodiment of this invention, certain minor changes in the construction, combination and arrangement of parts may be resorted to without departing from the spirit and scope of the invention as claimed.

What is claimed is—

1. A toy comprising a body, limbs pivoted to the body, means to cause the limbs to oscillate on pivots, a violin attached to one of the limbs, a bow having a slot therein to receive the violin, and a pivotal connection between the bow and one of the other limbs whereby when the limbs are oscillated the bow will travel over the violin.

2. The combination with a toy comprising a body, arms pivoted to the body, and means to move the arms outwardly on their pivots, of a bow comprising a body having a slot therein to receive the free end of one of the arms, a pair of parallel spaced extensions on the body, a violin on the other arm, operable between the extensions and means to limit the pivotal movement of the bow on the arm to which it is secured.

In testimony whereof I have affixed my signature.

MARTIN RYLL.
